(57) **CLAIM**

I claim the ornamental design for a mounting bracket for a personal electronic device, as shown and described.

DESCRIPTION

FIG. 1 is a top front perspective view of my design shown with jaws thereof in a closed configuration, a mount base shown as environmental structure;

FIG. 2 is a top front perspective view of my design shown with the jaws thereof in the closed configuration and taken from a point of view different from FIG. 1;

FIG. 3 is a top rear perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof;

FIG. 9 is a bottom view thereof;

FIG. 10 is a top front perspective view of the mounting bracket of FIG. 1 shown in an open configuration;

FIG. 11 is a top rear perspective view thereof as configured in FIG. 10;

FIG. 12 is a front view thereof as configured in FIG. 10;

FIG. 13 is a rear view thereof as configured in FIG. 10;

FIG. 14 is a right view thereof as configured in FIG. 10;

FIG. 15 is a left view thereof as configured in FIG. 10;

FIG. 16 is a top view thereof as configured in FIG. 10; and,

FIG. 17 is a bottom view thereof as configured in FIG. 10.

The broken lines shown illustrate environment that forms no part of the claimed design.
